SPRAY GUN

**Larry E. Pavey and Albert Allen Coe,
Seattle, Wash.**

Application December 13, 1948, Serial No. 150,122

Term of patent 14 years

(Cl. D62—2)

To all whom it may concern:

Be it known that we, Larry E. Pavey and Albert Allen Coe, both citizens of the United States of America, residing at Seattle, in the county of King, and State of Washington, have invented a new, original, and ornamental Design for a Spray Gun, of which the following is a specification, reference being had to the accompanying drawing, forming part thereof, wherein

Figure 1 is a side elevational view of one side of a spray gun embodying our new design; the opposite side of the spray gun is substantially identical with the side shown;

Figure 2 is a top plan view of the spray gun; and

Figure 3 is a transverse sectional view substantially on the line 3—3 of Figure 1.

We claim:

The ornamental design for a spray gun, substantially as shown and described.

LARRY E. PAVEY.

ALBERT ALLEN COE.
